UNITED STATES PATENT OFFICE.

LAURENCE A. HAWKINS, OF SCHENECTADY, NEW YORK, ASSIGNEE, BY MESNE ASSIGNMENTS, TO THE UNION SWITCH AND SIGNAL COMPANY, A CORPORATION OF PENNSYLVANIA.

BLOCK-SIGNAL SYSTEM.

1,102,917.

Specification of Letters Patent. Patented July 7, 1914.

Application filed August 7, 1909. Serial No. 511,663.

To all whom it may concern:

Be it known that I, LAURENCE A. HAWKINS, a citizen of the United States, residing at Schenectady, county of Schenectady, State of New York, have invented certain new and useful Improvements in Block-Signal Systems, of which the following is a specification.

My invention relates to block signal systems for railways and consists of a modification of the system disclosed in a companion application, Serial No. 511,663, filed August 7, 1909. In that application I disclosed a system in which the signals are arranged to give danger, caution and clear indications, either by two two-position arms or by one three-position arm, and in which the control of the signals is obtained without line wires by an arrangement comprising a pair of track relays for each block controlling the caution and clear indications, respectively, each having two coöperating windings, one connected to the track and the other supplied with alternating current independently of the track circuits, the currents in the latter windings of the two relays of each pair being different in character and preferably of different phase, with means controlled by a train in one block for changing the character of the track current in the preceding block, preferably by shifting its phase so as to energize first one and then both of the track relays of the preceding block. The principal advantages of that system, as compared with former wireless systems, are, first, that track relays of the most efficient type are employed, so that the current consumption is reduced to a minimum; second, since the relay controlling the caution indication is not even momentarily deenergized when the phase of the track current is shifted to energize the relay controlling the clear indication, it is unnecessary to employ a quick-acting switch for controlling the phase of the track current; and third, if the transformers of adjacent blocks are reversely connected the breaking down of the insulated joints between two adjacent block sections will always cause the relays adjacent to these joints to open their contacts, so that the signal controlled by them will be put at stop; thus, false clear indica-

tions possible in other wireless systems are impossible in this system.

My present invention consists in an extension of the system of my companion application for the purpose of obtaining an overlap; that is, of placing under the control of the train three signals behind it, so that the train may have two signals at stop position and one at caution or one at stop and two at caution behind it. To this end, I provide means controlled by train movements, for shifting the phase of the track current to three different positions and provide track relays responsive to variations in phase of the track current and responsive in three different combinations to the three different phases of the track current.

My invention will best be understood by reference to the accompanying drawings, in which—

Figure 1 shows diagrammatically a block signal system arranged in accordance with my invention; Figs. 2 to 6 inclusive are explanatory vector diagrams; Figs. 7 and 8 are diagrammatic views of the moving parts of certain of the relays; Fig. 9 shows a modification of the system; Figs. 10, 11, 12 and 13 are vector diagrams explanatory of the modification of Fig. 9; Fig. 14 shows a further modification of the system, in which the number of track relays is reduced; Figs. 15 to 18 are vector diagrams explanatory of Fig. 14; Fig. 19 shows a modification of the arrangement of Fig. 14 employing cut-sections arranged to give an overlap of half a block; Figs. 20 to 24 are vector diagrams explanatory of Fig. 19; Fig. 25 shows a further modification of the arrangement of Fig. 14 arranged to give an overlap of a complete block, and Figs. 26 to 28 are vector diagrams explanatory of Fig. 25.

In Fig. 1, A to A³ represent the track circuits of the blocks separated from each other by insulated joints. I have indicated one of the blocks as sub-divided, that is, composed of two cut-sections A' and A'', only a single track circuit being shown for each of the remaining blocks. B represents a three-phase generator for supplying alternating current for the signal circuits through the transmission wires b. C to C³ represent transformers having their prima-

ries connected to the several phases of the system. These transformers have their primaries T -connected so as to give two-phase voltages on their secondaries, in other words, they are connected in the well-known three-phase, two-phase manner. $c c$ represent impedances in circuit with the secondaries of these transformers. E to E^4 represent small track transformers, the primaries of which are supplied from the main transformers through the impedances $c c$ and the secondaries of which are connected to the track circuits. The impedances prevent the main transformers from being short-circuited when the track transformers are short-circuited by trains and also when the track transformers are being switched from one main transformer to another. D to D^{14} represent track relays of which three are shown for each track circuit. These relays are indicated diagrammatically as of the well-known induction type, each comprising a short-circuited member d actuating the relay contacts, a winding d' connected to the track and a second co-operating winding d^2 supplied with alternating current independently of the track circuit directly from the secondaries of the main transformers C to C^9 . F to F^3 represent signals for the blocks, which are arranged to give the three indications of danger, caution and clear.

In the drawings are shown diagrammatically one-arm three-position signals, but it will be understood that my invention is equally applicable to signals of any type or arrangement adapted to give the three said indications. The signal mechanisms are not shown in order to avoid complicating the drawings.

40 The movement of the signals from stop to caution takes place upon the closing of the contacts of the relays D , D^6 , D^9 and D^{12} , while the movement of the signals from caution to clear takes place upon the closing of the contacts of the relays D' , D^7 , D^{10} , and D^{13} . It will be understood that the conductor leading to the lower side of the blade is the common return and that the circuit controlling the movement from stop to caution is that which extends from the upper side of the blade directly to the contacts of relay D , D^6 , etc., while that controlling the movement from caution to clear comprises the conductor extending from the upper side 55 of the blade directly to the contacts of relay D' , D^7 , etc. f represents a movable contact or sector, mounted on the signal shaft or otherwise operated by the signal, provided with four stationary contact members f' to f'' . The connection between contact f and the signal is indicated diagrammatically by a dotted line. This contact in conjunction with relays D^2 , D^8 , D^{11} and D^{14} controls the connections of the track transformers E , E^2 , E^3 , E^4 to the secondaries of the main trans-

formers, and thereby controls the phase of the track current. It will be noted that the windings d^2 of the three relays for each track circuit are supplied with currents of different phase. The winding d^2 of relay D , for instance, is connected across the secondary of transformer C , while the corresponding windings of relays D' and D^2 are connected across a portion of the secondary of transformer C' , and, consequently, have impressed upon them voltages displaced in phase 90° from that impressed on winding d^2 of relay D . Furthermore, the windings d^2 of relays D' and D^2 are reversely connected with respect to each other, so that the currents in the winding of these two relays may be said to be displaced from each other by 180° while the current in the corresponding winding of relay D has an intermediate position.

85 The operation of the system is as follows: With a train in track section A^5 the track windings of the three relays D^{12} , D^{13} and D^{14} are short-circuited, so that all three relays open their front contacts and signal F^3 stands at danger or stop position. The conditions in the windings d^2 of the three relays are as indicated in the vector diagram of Fig. 2, in which $o v'$ represents the voltage impressed on the winding d^2 of relay D^{12} and $o i'$ the current in that winding which lags behind the voltage by a considerable angle. Similarly, the voltage and current of winding d^2 of relay D^{13} are indicated by $o v^2$ and $o i^2$, respectively, and in winding d^2 of relay D^{14} by $o v^3$ and $o i^3$. Since the relay D^{14} has its front contacts open and its back contact closed the circuit of the primary of track transformer E^4 extends from the left-hand terminal of the primary winding through contacts f^3 , f and f' , back contacts of relay D^{14} , to the right-hand terminal of the secondary of main transformer C^9 , through half the winding of this transformer and from the central tap through the impedance c to the right-hand terminal of the primary of transformer E^4 . The primary of the track transformer is thus connected through impedance c to the secondary of transformer C^9 , the voltage of which is the voltage impressed on the winding d^2 of relay D^{14} . If the impedance c is non-inductive, the track circuit and this impedance together have a fairly high power factor, so that the track current in track circuit A^4 may be represented by $o i$ in Fig. 3 lagging by a comparatively small angle behind the voltage $o v^3$. If the circuits are properly arranged the angle i $o i^3$ may be made approximately 45° . If it is desired to use inductive impedances, the desired phase relation may be obtained by impressing the proper voltages on the windings d^2 of the relays, and since two-phase voltages from the secondaries of the transformers C^8 and C^9 130

are available the phases of the voltages impressed on these windings of the relays may be made anything desired.

Since the phase of the track current in track circuit A^4 may be represented by $o i$ in Fig. 3, this figure shows the conditions in relays D^8 , D^{10} and D^{11} . It will be seen that the track current $o i$ leads the current $o i^2$ in winding d^2 of relay D^{11} and lags behind the current in the corresponding windings of relays D^8 and D^{10} by 45° and 135° respectively. If the relays are so wound or connected that when the current in the track winding leads the current in the other winding a torque is produced tending to close the front contacts of the relay, then relay D^{11} will have such a torque while relays D^8 and D^{10} will have a reverse torque. Relay D^{11} has, consequently, closed its front contacts and opened its back contacts as indicated. In doing so it has not interrupted the flow of current to track circuit A^4 , since its contacts are arranged, as indicated, somewhat diagrammatically, in Figs. 7 and 8, that is, flexible contacts d^8 are used so that the front contacts d^8 close before the back contacts d^4 are opened. During the time that both front and back contacts are closed the secondary of transformer C^8 is in parallel with the secondary of transformer C^7 , so that the current in track circuit A^2 during this time is the resultant of the current of these two transformers and consequently advanced in phase by 45° .

It will be seen, by considering the effect of advancing the current $o i$ in Fig. 3 by 45° , that the only results are to increase somewhat the torque in relay D^8 corresponding to relay D^{11} , since the currents in the two windings are then displaced from each other by approximately 90° instead of by only 45° , and to destroy the reverse torque in relay D^8 corresponding to relay D^8 , since the currents in the two windings are then in phase. This relay would still, however, be held in open circuit position by gravity. During this time some current flows through the secondaries of transformers C^8 and C^7 in series, but is limited in amount since it must flow through both impedances o in series. As relay D^{11} completes its movement and opens its back contacts, transformer C^8 alone is connected to the primary of track transformer E^8 , the circuit extending through contacts f^8 , f^7 , f^2 and front contacts of relay D^{11} . The phase of the current in track circuit A^2 is, consequently, displaced 90° from that in track circuit A^4 and the conditions in relays D^8 , D^7 and D^8 may be represented by Fig. 4. It will be seen from this figure that the track current $o i$ leads the current in the winding d^2 of relays D^8 and D^8 by 135° and by 45° , respectively, while it lags behind the current in the winding d^2 of relay D^7 by 45° . Comparing Figs. 4 and

it will be seen that the torque in relay D^8 is the same as in relay D^{11} , since the sine of 135° is the same as the sine of 45° . Comparing relays D^8 and D^8 it will be seen that relay D^8 now has a torque tending to close the contacts, of the same amount as the reverse torque in relay D^8 . Comparing relays D^7 and D^{10} it will be seen that there is an equal reverse torque in both relays since the sine 45° is the same as the sine of 135° . Relay D^8 has, consequently, closed its contacts, and this closes the circuit controlling the movement of signal F' from stop to caution. While the signal makes this movement the contact f first leaves contact f^2 and then engages contact f^4 . Contact f^2 through the back contacts of relay D^8 and contact f^4 directly, are connected to opposite terminals of the secondary of transformer C^8 , so that, if, when a train entered the block, relay D^8 closed its back contacts before signal F' had moved to stop position and if contact f could engage contacts f^2 and f^4 simultaneously, transformer C^8 would be short-circuited. For this reason contacts f^2 and f^4 are arranged so that one opens before the other does as indicated in dotted lines at signal F' . Contact f^4 is however engaged before contact f^2 is disengaged from contact f . At this time the left-hand half of the secondary of transformer C^8 is connected in parallel with the secondary of transformer C^7 . This again advances the phase of the track current of track circuit A^2 45° , and then, when contact f leaves contact f^2 , transformer C^8 is disconnected from transformer E^8 and the phase of the current in track circuit A^2 has now been advanced 90° without interrupting its flow. Conditions in relays D^8 , D^7 and D^8 are then as indicated by the vector diagram of Fig. 5. Comparing this figure with Fig. 4 it will be seen that the track current $o i$ has been advanced 90° . Comparing relay D^8 with relay D^8 it will be seen that the track current now lags 135° behind the current $o i^2$ instead of leading it by that angle, so that the torque in relay D^8 is a reverse torque and the relay has opened its contacts. Assuming for a moment that there is a signal at relays D^8 , D^4 and D^8 and that the signal circuits are connected as shown for signal F' , it will be seen that the opening of the front contacts of relay D^8 would have no effect on the track current of the next block, since with the signal at caution position the connections to the primary of the track transformer are made directly through the signal contacts independently of the contacts of relay D^8 . Comparing relay D^8 with relay D^8 it will be seen that the track current $o i$ leads the current $o i^2$ in relay D^8 by 135° instead of by 45° as in relay D^8 and the torques of relays D^8 and D^8 are, consequently, the same. Comparing

relay D^4 with relay D^7 it will be seen that the track current leads the current $o i^2$ by 45° in relay D^4 instead of lagging behind it by that angle as in relay D^7 . The torque of relay D^4 tends to close the relay contacts and if there were a signal at this relay connected as shown for signal F' the signal would be moved from caution to clear position. In order to illustrate the application of the system to a cut-section, no signal is shown at these relays, the contacts of which are arranged to control the circuit of the primary of track transformer E' of track circuit A' . It will be seen that if a train were in section A^2 , so that all three relays D^3 , D^4 and D^5 were deenergized, the primary circuit of transformer E' would be opened, relays D , D' and D^2 would be deenergized, and signal F' would stand at stop position. With a train in section A^3 the conditions of relays D^3 , D^4 and D^5 would be the same as that shown for relays D^9 , D^{10} and D^{11} in Fig. 3, that is, relay D^5 would be energized and relays D^3 and D^4 would be deenergized. Under these conditions the left-hand primary terminal of track transformer E' would be connected through the back contact of relay D^3 and front contacts of relay D^5 to the right-hand secondary terminal of transformer C^3 . In other words, track transformer E' would then be connected precisely as shown for track transformer E^4 , the conditions of relays D , D' and D^2 would be the same as the condition of the relays for track section A^4 as shown in the figure, and the signal F would still remain at stop; in other words, a train in section A^3 holds signal F at stop and, consequently, the signal next in the rear at caution.

When a train is in section A^4 the condition of relays D^3 , D^4 and D^5 will be as shown in Fig. 4 for relays D^6 , D^7 and D^8 ; that is, relays D^3 and D^5 would be energized while relay D^4 would be deenergized. The left-hand primary terminal of transformer E' is now connected through the front contacts of relay D^3 and the back contacts of relay D^4 to transformer C^2 so that transformer E' would be connected precisely as transformer E^3 is shown connected. Consequently, the condition of relays D , D' and D^2 would under these conditions be the same as shown for relays D^6 , D^7 and D^8 and the signal F would, consequently, move to caution. The contacts of relay D^3 are made flexible in the manner before described, so as to close the front contacts before opening the back and thereby to shift the phase of the current in track circuit A' without interrupting its flow. With a train in block A^5 the relays D^3 and D^4 are energized as already described, while relay D^5 is deenergized. The left-hand primary terminal of transformer E' is now connected through the front con-

tacts of relays D^3 and D^4 to the left-hand secondary terminal of transformer C^3 , so that transformer E' is now connected exactly like transformer E^2 . Consequently, the condition of relays D , D' and D^2 is the same as that of relays D^3 , D^4 and D^5 and is as shown by the vector diagram of Fig. 6. The signal F has, consequently, moved from caution to clear position as shown. During this movement no change in circuit connections is produced by the contact f , so that the conditions in the track circuit A have not been altered. It will thus be seen that by arranging the contacts of the track relays of cut-sections to establish the same connections under the same conditions as are established by the contacts on the signal shaft, the control may be carried back through as many cut-sections as desired without interfering with the operation of the system.

The reason that the three leads are taken from the secondaries of transformers C' , C^3 , C^5 , etc., is simply to provide a convenient means for deriving from this transformer two voltages displaced in phase from each other by 180° , that is, to obtain the conditions shown in Fig. 3 on one hand and in Fig. 6 on the other, with a simple arrangement of wiring and contacts.

It will be seen that the connections of track transformers of adjacent track sections are relatively reversed and also that the connections of relays of adjacent track circuits are relatively reversed. Since the track relays are reversed in the same track circuits in which the track transformers are reversed, this reversal has not heretofore been mentioned, since so far as the operation of each block considered by itself is concerned this double reversal is of no effect. It becomes of importance, however, in the case of leakage of current from one track section to the next, due to the breaking down of insulated joints, or from any other cause. In such a case the current that leaks to the relays is in a direction opposite to that which the same current has upon the relays of its own track circuit, so that no false clear indication can be obtained because of this leakage. The precise effect of such leakage current through broken down joints on each of the three relays, under different conditions corresponding to different positions of the signal controlled by these relays, will be obvious from a consideration of the vector diagrams and need not be described in detail. It will be noted that under some conditions broken down joints between track sections will first put a signal to stop and then cause it to move a short distance from stop toward caution only to return again to stop and repeat the operation. In other words, in the arrangement of Fig. 1 a broken down joint is, under certain conditions, indicated by a wigwagging of the signal through a

short arc near stop position and under other conditions by the signal going to and remaining at stop.

With the arrangement of Fig. 1 a train always has two signals at stop and one at caution behind it. The contacts and control circuits may be modified as shown in Fig. 9 to give one signal at stop and two at caution, the length of the zone of control at the rear of the train being the same as in Fig. 1. Three relays per track section are provided as in Fig. 1 but the connections of the relay windings d^2 of relays, D_1 and D_2 , or D_1 and D_3 , etc., are relatively reversed, as indicated in Fig. 10 as compared with Fig. 2, $\sigma v'$ in all figures indicating the voltage impressed on winding d^2 of the relay controlling the original movement from stop to caution, that is, D_1 , D_2 , D_3 , etc., while $\sigma v''$ represents the voltage for relays D_2 , D_3 , D_4 , etc. The connections of the contacts of relays D_2 , D_3 , etc., are somewhat modified as will best be understood by considering the conditions in the several blocks shown. With a train in section A' the relays D_1 , D_2 , and D_3 , are all deenergized, there being no track current in these relays, as indicated in Fig. 10; the signal F^2 consequently stands at stop.

The track transformer E^2 has its primary connected through contacts f^2 , f , f' and impedance c to the right-hand secondary terminal of transformer C^2 , so that the phase of the current in track circuit A^2 is as indicated by σi in Fig. 11 which shows the conditions in relays D_1 , D_2 , and D_3 . It will be seen in this diagram that relay D_1 is energized while relays D_2 and D_3 have reverse torques. Signal F^2 is, consequently, moved from clear to caution position and transformer C^2 is connected to the left-hand terminal of track transformer E^2 through contacts f^2 , f , f' , impedance c , back contact of relay D_1 , to the secondary of transformer C^2 . The track current in track circuit A^2 is, consequently, advanced 90° with respect to track circuit A^3 and the conditions in relay D_2 , D_3 , and D_4 , are as indicated in Fig. 12. It will be seen from this figure that relays D_1 and D_2 , are both energized so that signal F^2 remains at caution, while relay D_3 , has shifted the connection of the left-hand terminal of track transformer E^2 from transformer C^2 to the left-hand terminal of transformer C^3 . Relay D_4 , closed its front contacts before opening its back contacts, so that the current flow in track circuit A' is not interrupted but is advanced by 90° as represented by σi in Fig. 13. It will be seen from this figure, which shows the conditions in relays D_1 , D_2 , and D_3 , that relays D_1 and D_2 , are energized while relay D_3 , is deenergized. The deenergization of relay D_3 , has not affected signal F^2 since its contacts have been shunted by the upper front con-

tacts of relay D_2 , while the closing of the contacts of relay D_1 , has caused the signal to move from caution to clear. During this movement the contact f has made no change in the circuit connections of transformer E^2 , so that the track section A has not been affected.

In Figs. 1 and 9 three relays per track section have been employed for obtaining the three different combinations corresponding to the three phases of the track current. It will be seen, however, that three different conditions can be obtained with only two relays; that is, with each of the two relays energized singly and both of the relays energized simultaneously. Such a modification is shown in Fig. 14 in which relays D_2 , D_3 , D_4 , etc., of Fig. 1 are omitted and relays D_1 , D_2 and D_3 , etc., caused to perform the function of the omitted relays. The two-function relays are indicated in Fig. 14 at D_2' , D_3' , D_4' , and D_5' . Relays D_2' , D_3' , D_4' , and D_5' , correspond to relays D_1 , D_2 , and D_3 , etc., of Fig. 1. The windings d^2 of relays D_2' , D_3' , D_4' , and D_5' , of Fig. 14 are controlled by the contacts f^2 on the signal shaft in such a manner that the current in the relay winding is reversed at certain times, so as to cause it at one time to respond to current of a certain phase and at another time to current of another phase. The operation of this modification will best be understood by considering the conditions in the several track sections shown. With a train in section A' , as shown, both relays D_2' , D_3' , are deenergized and the signal F^2 stands at stop. The conditions in winding d^2 of the relays are shown in Fig. 15 in which $\sigma v'$ and $\sigma i'$ relate to relay D_2' . The winding d^2 of relay D_2' is connected through contacts f^2 , f , and f' to the right-hand secondary terminal of transformer C^2 . With this connection this relay corresponds in its operation to relay D_1 of Fig. 1. The left-hand primary terminal of transformer E^2 is connected through contacts f^2 , f , and f' , back contacts of relay D_2' , and impedance c to the right hand terminal of the secondary of transformer C^2 . Transformer E^2 is thus connected the same as transformer E^4 in Fig. 1 and the conditions in relays D_4' , and D_5' , are as represented by Fig. 16. It will be seen from this figure that only relay D_2' , has a torque tending to close its contacts while relay D_3' , is deenergized. Signal F^2 , consequently, remains at danger but the connections for the left-hand terminal of transformer E^2 have been transferred from transformer C^2 to transformer C^4 by the closing of the front contacts of the relay D_2' and the opening of the back contacts. The upper contacts of relay D_2' , while closing have not affected the signal F^2 since they are open-circuited at the contacts of relay D_4' . The transformer E^2 being connected to the

transformer C^4 the current in track circuit A^2 is advanced 90° with respect to the current in track circuit A^3 . By considering Fig. 16 showing the conditions in track A^3 it will be seen that the first effect of advancing the current $o i$ would be to energize relay D^4_2 without deenergizing relay D^5_2 , which would result in starting the movement of the signal from stop to caution position. 5 In the course of this movement contact f^4 first leaves contact f^5 and then engages f^7 . This reverses the connection of the winding d^2 of the relay and, consequently, produces the conditions at relays D^4_2 and D^5_2 shown in Fig. 17. Comparing this figure with Fig. 16 it will be seen first that relay D^4_2 has a positive torque instead of a reverse torque, while, since the voltage and current in winding d^2 of relay D^4_2 , represented by $o v^2$ and $o i^2$, are reversed in phase as compared with Fig. 16, the relay D^4_2 has been deenergized through the reversal of its connections. Signal F' , consequently, moves to caution position but stops there. During this motion the contact f has shifted the connection from the left-hand terminal of transformer E' from transformer C^2 to the left-hand terminal of the secondary of transformer C^3 . This connection has been established through contact f^3 before contact finger f^6 was open-circuited as indicated in dotted lines at signal F' and consequently before relay D^3_2 was deenergized, so that the current flow in track circuit A' was not interrupted. The 35 conditions in relays D^4_2 and D^5_2 are now as represented by Fig. 18, from which it will be seen that both relays D^4_2 and D^5_2 are energized and the signal F has moved to clear position. During this movement the contacts f and f^4 make no further change in the circuit connections.

Fig. 19 shows a modification of Fig. 14 adapted for use where cut-sections are employed and where an overlap of less than a 45 complete block is required. This figure shows two cut-sections per block with an overlap of one cut section or half a block. The connections of the relay windings are the same as in Fig. 14 but the contact connections are somewhat altered. With a train in section A^6 relays D^4_3 and D^5_3 are deenergized, the conditions in these relays being as shown in Fig. 20. The primary of transformer E^4 is open-circuited at the lower 55 front contacts of relay D^6_3 so that relays D^6_3 and D^7_3 are also open-circuited. The voltages and currents of the windings d^2 of these relays are as shown in Fig. 21. The left-hand primary terminal of transformer E^3 is connected through the back contacts of relay D^6_3 to the right-hand terminal of transformer C^7 , so that the conditions in relays D^4_3 and D^5_3 are as indicated in Fig. 22. 60 The relay D^5_3 is consequently energized connecting the left-hand primary terminal of

transformer E^2 to transformer C^4 so that the conditions in relays D^2_3 and D^3_3 are as indicated in Fig. 23. Relay D^2_3 is, consequently, energized while relay D^3_3 is deenergized. Transformer E' is connected 70 through the front contacts of relay D^3_3 and back contacts of relay D^2_3 to transformer C^2 , so that the conditions in relays D^2_3 and D^3_3 are the same as in relays D^4_3 and D^5_3 , as indicated by Fig. 24. Relay D_3 being energized, signal F has gone to caution position, and winding d^2 of relay D^4_3 has been reversed, as indicated by comparing Fig. 24 and Fig. 22. Thus a train in section A^6 has behind it two signals at stop and one at caution. When the train moves out of section A^6 to the next section beyond, the condition of relays D^4_3 and D^5_3 becomes the same as shown for relays D^4_2 and D^5_2 . Consequently, the conditions of relays D^4_3 and D^5_3 becomes the same as shown for relays D^4_2 and D^5_2 , and the signal F' moves to caution position. This changes the connections of transformer E^2 from transformer C^4 to transformer C^3 , shifting the phase of the current in track section A^2 90° so as to energize relay D^3_2 , which shifts the connection of transformer E' from transformer C^2 to transformer C^3 , thereby energizing relay D^4_2 and clearing signal F . That is, with a 90 train in the second or outgoing section of the block it has behind it one signal at stop and one at caution. In other words, the overlap obtained with Fig. 19 is of one cut-section or half a block. The two relay arrangement 100 may equally well be arranged to give a complete block overlap as shown in Fig. 25. In this figure the windings of relays D^4_2 and D^4_3 are connected the same as those of relays D^4_3 and D^5_3 in Fig. 19. Relays D^4_2 and D^5_4 are also connected as relays D^4_3 and D^5_3 are connected in Fig. 19. Relay D^2_4 is connected the same as D^2_3 in Fig. 19 but relay D^3_4 has its winding d^2 controlled by relay D^2_4 , so that it is reversed when relay D^2_4 is 110 energized or deenergized. This makes the connection and operation of relay D^3_4 the same as relays D^4_2 and D^5_4 . With a train in section A^6 relays D^4_2 and D^5_4 are deenergized, the voltages and currents in their windings 115 d^2 being as shown in Fig. 26. The left-hand terminal of transformer E^2 is connected through contacts f^2 , f , f^4 and back contacts of relay D^6_4 to transformer C^3 and the conditions in relays D^2_4 and D^3_4 are as indicated by Fig. 27. Relay D^2_4 being deenergized, the connection of winding d^2 of relay D^3_4 is the same as that of relay D^4_2 , as is seen by comparing Figs. 26 and 27. Relay D^3_4 , consequently, is energized and 120 transformer E' is connected through the back contacts of relay D^6_4 and front contacts of relay D^2_4 to transformer C^3 , so that transformer E' is connected the same as transformer E^2 and conditions in relays D^4_2 125 and D^5_4 are the same as in Fig. 24. 130

and D'_4 are the same as in relays D^2_4 and D^3_4 , as indicated by Fig. 28. When the train moves out of section A^2 to the next section beyond, the conditions with respect to relays D^2_4 and D^3_4 will become the same as the conditions of relays D_4 and D'_4 would be with a train in section A^2 . With a train in section A^2 both relays D^2_4 and D^3_4 are deenergized and the primary circuit of transformer E' is open at the front contacts of relay D^3_4 , so that relays D_4 and D'_4 are both deenergized. In other words, as long as the train is in either of the sections forming the block guarded by signal F' the signal remains at stop, relays D^2_4 and D^3_4 remain deenergized, and the conditions in track circuits A' and A^2 remain as shown. When the train moves out of the block guarded by signal F' the conditions at relays D^2_4 and D^3_4 become the same as shown for relays D_4 and D'_4 . Signal F' , consequently, remains at stop but transformer E^2 is then connected as transformer E is shown connected in the drawing; that is, to transformer C or C' . When the transformer E^2 is thus connected the current is advanced 90° in section A^2 , which, by an inspection of Fig. 27 will be seen to have the effect of energizing relay D^2_4 which, after closing its front contacts, reverses the connections of the winding d^2 of relay D^3_4 , which then becomes deenergized. Under these conditions the connection of transformer E' extends through the front contacts of relay D^2_4 and back contacts of relay D^3_4 to transformer C^2 , so that the phase of the current in track circuit A' is also advanced 90° . This energizes relay D_4 , and causes signal F to move from stop to caution position, which by its movement reverses the winding d^2 of relay D'_4 and deenergizes that relay. This shifts the connection of transformer E from transformer C to transformer C' again advancing the phase of the current in section A 90° . The effect of this advance may be understood by considering the effect of reversing the phase of the current in track section A^2 , it being remembered that relay D^2_4 is already energized and that relay D^3_4 has its winding d^2 reversed from what is shown in Fig. 27.

It will be seen that under these conditions, the current $o i$ being reversed from what is shown in Fig. 27, both relays D^2_4 and D^3_4 would be energized and transformer E' would be connected through the front contacts of the two relays in series to the left-hand secondary terminal of transformer C^2 . This would again advance the current in track section A' and it will be seen from an inspection of Fig. 28, remembering that $o v^2$ and $o i^2$ have been reversed, that a current opposite in phase to $o i$ of Fig. 28, will energize both relays D_4 and D'_4 to cause the signal to move from caution to clear, during

which movement no change affecting the track circuits in the rear is made. Thus, the arrangement of Fig. 25 gives a complete block overlap.

In all the arrangements shown the number of track sections per block may be varied as desired, the amount of overlap may be made any number of track sections not exceeding a complete block, and numerous different relay combinations may be employed. I, therefore, do not desire to limit myself to the particular connections and arrangements of parts shown and described. Also, although I have described a system in which the current is caused to change its phase to produce the desired signal indications, it will be understood that any other modification of the current that involves a distinct change in character might be employed, and I aim in the appended claims to cover all modifications that are within the scope of my invention, whether the change in the character of the current employed is a change in phase or otherwise.

What I claim as new and desire to secure by Letters Patent of the United States is:

1. In a block signal system, track circuits for the blocks, sources of alternating current for the track circuits, means controlled by a moving train for causing the current supplied to a track circuit to assume three distinct characters successively as the train passes through the blocks in advance, and means responsive in three different ways to the three characters of the track current, said means including a plurality of track relays for said track circuit, the several relays of said track circuit being differently responsive to variations of character of the track current.

2. In a block signal system, track circuits for the blocks, sources of alternating current for the track circuits, means controlled by a moving train for causing the current supplied to a track circuit to assume three distinct characters successively as the train passes through the blocks in advance, and means responsive in three different ways to the three characters of the track current, said means including a plurality of track relays for said track circuit, said first-named means including a like plurality of relays in each of the blocks in advance, the several relays of any one track circuit being differently responsive to variations of character of the track current, signals for the blocks arranged to indicate danger, caution and clear, and control circuits for said signals controlled by the different combinations of track relays pertaining to the corresponding blocks, whereby three signals behind a train are held in danger and caution positions, one in one of said positions and two in the other.

3. In a block signal system, track circuits for the blocks, sources of alternating current

- for the track circuits, means controlled by a moving train for causing the current supplied to a track circuit to assume three distinct characters successively as the train
5. passes through the blocks in advance, and a plurality of track relays for said track circuit each having a winding supplied with current from the track and a second coöperating winding supplied with alternating
10. current from a source aside from the track, the currents in said second winding differing in character in the several relays for said track circuit.
4. In a block signal system, track circuits, 15. sources of polyphase alternating current for the track circuits, means controlled by a moving train for shifting the phase of the current supplied to a track circuit to three distinct positions, whereby said current has
20. three different phases successively as the train passes through the blocks in advance, and means responsive in three different ways to the three phases of the track current, said means including a plurality of track relays
25. for said track circuit, the several relays of said track circuit being differently responsive to variations of phase of the track current.
5. In a block signal system, track circuits 30. for the blocks, sources of polyphase alternating current for the track circuits, means controlled by a moving train for shifting the phase of the current supplied to a track circuit to three distinct positions, whereby said
35. current has three different phases successively as the train passes through the blocks in advance, and means responsive in three different ways to the three phases of the track current, said means including a plurality of track relays for said track circuit,
40. and said phase-shifting means including a like plurality of relays for each of the three blocks in advance, the several relays of any one track circuit being differently responsive to variations of phase of the track current, signals for the blocks arranged to indicate danger, caution and clear, and control circuits for said signals controlled by the different combinations of track relays
45. pertaining to the corresponding blocks whereby three signals behind a train are held in danger and caution positions, one in one of said positions and two in the other.
6. In a block signal system, track circuits 55. for the blocks, sources of polyphase alternating current for the track circuits, means controlled by a moving train for shifting the phase of the current supplied to a track circuit to three distinct positions, whereby said
60. current has three different phases successively as the train passes through the blocks in advance, and a plurality of track relays for said track circuit each having a winding supplied with current from the track and a second coöperating winding supplied with
65. alternating current from a source aside from the track, the currents in said second windings differing in phase in the several relays for said track circuit, said phase-shifting means being arranged to shift the phase of
70. 75. 80. 85. 90. 95. 100. 105. 110. 115. 120. 125. 130.
- with alternating current from a source aside from the track, the currents in said second windings differing in phase in the several relays for said track circuit.
7. In a block signal system, track circuits, sources of polyphase alternating current for the track circuits, means controlled by a moving train for shifting the phase of the current supplied to a track circuit to three distinct positions, whereby said current has three different phases successively as the train passes through the blocks in advance, a plurality of track relays for said track circuit each having a winding supplied with current from the track and a second coöperating winding supplied with alternating current from a source aside from the track, the currents in said second windings differing in phase in the several relays for said track circuit, said phase-shifting means including a like plurality of relays for each of the three blocks in advance, signals for the blocks arranged to indicate danger, caution, and clear, and control circuits for said signals controlled by the track relays pertaining to the corresponding blocks whereby three signals behind a train are held in danger and caution positions, one in one of said positions and two in the other.
8. In a block signal system, track circuits for the blocks, sources of polyphase alternating current for the track circuits, means controlled by a moving train for shifting the phase of the current supplied to a track circuit to three distinct positions, whereby said current has three different phases successively as the train passes through the blocks in advance, and means responsive in three different ways to the three phases of the track current, said means including a plurality of track relays for said track circuits, the several relays of said track circuit being differently responsive to variations of phase of the track current, said phase-shifting means being arranged to shift the phase of the track current gradually without interrupting its flow.
9. In a block signal system, track circuits for the blocks, sources of polyphase alternating current for the track circuits, means controlled by a moving train for shifting the phase of the current supplied to a track circuit to three distinct positions, whereby said current has three different phases successively as the train passes through the blocks in advance, and a plurality of track relays for said track circuit each having a winding supplied with current from the track and a second coöperating winding supplied with alternating current from a source aside from the track, the currents in said second windings differing in phase in the several relays for said track circuit, said phase-shifting means being arranged to shift the phase of

the track current gradually without interrupting its flow.

10. In a block signal system, track circuits for the blocks, sources of polyphase alternating current for the track circuits, means controlled by a moving train for shifting the phase of the current supplied to a track circuit to three distinct positions, whereby said current has three different phases successively as the train passes through the blocks in advance, and means responsive in three different ways to the three phases of the track current, said means including a plurality of track relays for said track circuits, the several relays of said track circuit being differently responsive to variations of phase of the track current, the connections of adjacent track circuits being relatively reversed so that the currents in adjacent track circuits under similar conditions are relatively opposed in phase.

11. In a block signal system, blocks having cut sections, track circuits for the sections, sources of polyphase current for the track circuits, a plurality of track relays for each track circuit responsive to change of phase of the track current, contacts controlled by the track relays of each block for controlling the current supplied to the adjacent track circuit of the block next in the rear, the contacts controlled by the track relays of the last-mentioned track circuit operating to shift the phase of the current supplied to the track circuit next in the rear to three distinct positions, the track relays of the last-mentioned track circuit being responsive in three different combinations to the three different phases of the track current.

12. In a block signaling system, blocks having cut sections, track circuits for the sections, sources of polyphase current for the track circuits, a plurality of track relays for each track circuit responsive to change of phase of the track current, contacts controlled by the track relays of each block for controlling the current supplied to the adjacent track circuit of the block next in the rear, the contacts controlled by

the track relays of the last-mentioned track circuit operating to shift the phase of the current supplied to the track circuit next in the rear to three distinct positions, the contacts for establishing the connections for one of the phases of the current being arranged to close before those establishing the connections of another phase open, the track relays of the last-mentioned track circuit being responsive in three different combinations to the three different phases of the track current.

13. In a block signal system, track circuits for the blocks, sources of polyphase current for the track circuits, a plurality of track relays for each track circuit responsive to variations of phase of the track current, and responsive in different combinations to the different phases of the track current; means controlled by said relays for varying the phase of the current supplied to a track circuit, and for varying the connections of a relay to cause it to respond at different times to different phases of the track current.

14. In a block signal system, track circuits for the blocks, sources of polyphase current for the track circuits, a plurality of track relays for each track circuit each having a winding supplied with current from the track and a second coöperating winding supplied with alternating current from a source distinct from the track, the currents in the second windings differing in the several relays for each track circuit; means controlled by said relays for varying the phase of current supplied to a track circuit and for controlling the current in said second winding of a track relay to cause said relay to respond at different times to different phases of the track current.

In witness whereof, I have hereunto set my hand this 5th day of August, 1909.

LAURENCE A. HAWKINS.
